UNITED STATES PATENT OFFICE.

MAURICE LOUIS JOSEPH RICHARD, OF QUEBEC, QUEBEC, CANADA.

TOY.

1,344,451.

Specification of Letters Patent. Patented June 22, 1920.

Application filed April 28, 1919. Serial No. 293,163.

To all whom it may concern:

Be it known that I, MAURICE LOUIS JOSEPH RICHARD, residing at 658 St. Valier street, in the city of Quebec, in the Province 5 of Quebec, in the Dominion of Canada, have invented certain new and useful Improvements in Toys; and I do hereby declare that the following is a full, clear, and exact description of the same.

10 The present invention relates to improvements in a toy which consists of a knock down house composed of a plurality of blocks of different length, adapted to provide for openings such as windows and doors.

15 A feature of this invention is the provision of a building block outfit in which the different members noticeably differ in size and shape from each other whereby the toy may be used by young children who 20 would be perplexed with the building block outfits heretofore known in which numerous different shaped parts having slight differences between them are provided.

25 The main object of this invention is to provide a toy that will be agreeable to children, and particularly simple, cheap and durable.

30 Another of the objects is to devise a game or toy of this character which will be instructive and which small children as well as older ones may find pleasure in playing with.

35 The invention will be better understood with the aid of the accompanying drawings in which:

Figure 1 is a perspective view of a house constructed according to the invention.

Fig. 2 is a view of a house partly pulled down and a detail of the blocks which form 40 part of the house.

Fig. 3 is a perspective view of the blocks provided with a plurality of depressions to simulate brick or stone.

45 Like numerals of reference indicate corresponding parts in each figure.

In the drawings 1 are a plurality of blocks preferably the length of the house which are adapted to form the front and rear sides. These blocks are superposed 50 over one another as indicated in Fig. 2 of the drawings and 2 are blocks mounted over the top blocks 1, preferably much shorter in length in relation to the said blocks 1 and so spaced apart as to form 55 an intermediate opening. Above said blocks 2 are mounted in superposed relation to one

another four rows of short blocks 3 so arranged as to form a plurality of openings and on top of these blocks are mounted two blocks 4 of the same length as the blocks 60 1 and adapted to close the window openings 5 and central door openings 6. The blocks 3 are noticeably shorter than the blocks 2.

At each end of said blocks 1, 2, 3 and 65 4 are provided a plurality of blocks 7 superposed over one another and of the width of the house. Above said blocks are mounted a plurality of blocks 8 noticeably shorter in length than the blocks 7 and so 70 75 spaced apart as to form a window opening 9 and 10 are blocks preferably of the same length as the blocks 7 mounted above said blocks 8 and adapted to close said opening 9. The blocks 7, 8, and 10 must correspond in height and number to blocks 1, 2, 3 and 4 in order that the sides of the house as well as the the ends will be of the same height.

Above the top blocks 10 which are provided at each end of the house two triangular members 11 and 12 are provided which are adapted to form a V shape member supporting the roof boards 13 and 14. The roof boards 13 and 14 are preferably 85 secured together at one of their edges by a pasted strip 15 or any other suitable means and 16 is the chimney which is saddled over the apex of the angle formed by the roof, the said chimney comprising a 90 square block having a V-shaped cut 17 on one side thereof which is adapted to fit snugly over the roof.

In the front side of the house are provided the blocks 18 which are disposed at 95 right angle in relation to the blocks 1 and 19 is a step composed of two blocks and a third block superposed over one of said blocks, said step block being disposed parallel to the sides of the house and forming in combination with the blocks 18 a base or support for the floor board 20.

Provided on top of said floor board 20 are four posts 21 and 22, the posts 21 being mounted against the sides of the house and 105 cut at an angle at their uppermost end, while the posts 22 preferably shorter in length than the post 21 and cut at their uppermost end at a corresponding angle, the said posts being adapted to support the incline 110 roof board 23.

At their lower ends and between said

posts 21 and 22 is provided on each side of said floor board 20 a short block 24 which is adapted to serve as railing.

Each block is provided on one side there-
5 of with a plurality of transverse saw cuts
25 so arranged as to give to the house the
appearance of stone or brick walls, or if
it is preferred to show a log or board house
the plain side of the block is used.

10 10 What I claim as my invention is:

1. A child's building block outfit for con-
structing toy houses consisting of three
distinct sets of rectangular blocks, the
blocks of each set differing noticeably in
15 length from the blocks of the other two sets
said three sets of blocks being principally
designed for building the walls of a house
and comprising the main pieces of the out-
fit; and a set of supplemental pieces for
20 constructing details of the house other than
the walls, the supplemental pieces having
plain rectilinear faces, the different pieces
thereof being noticeably different in size
and shape from one another and from the
25 main blocks.

2. A child's building block outfit for con-
structing toy houses consisting of three dis-
tinct sets of rectangular blocks, the blocks
of each set differing noticeably in length
from the blocks of the other two sets said 30
three sets of blocks being principally de-
signed for building the walls of a house and
comprising the main pieces of the outfit;
and a set of supplemental pieces for con-
structing details of the house other than 35
the walls, the supplemental pieces having
plain rectilinear faces, the different pieces
thereof being different in size and shape
from one another and from the main blocks,
the opposite faces of the rectilinear blocks 40
forming the main pieces of the outfit be-
ing constructed to indicate building mate-
rial of different characters.

Signed at Quebec, Quebec, Canada, this
23d day of April, 1919.

MAURICE LOUIS JOSEPH RICHARD.
